CIRCUIT CONTROLLING ATTACHMENT FOR
TOY TRACKSMarshall H. Frisbie, Hamden, Conn., assignor to
The A. C. Gilbert Company, New Haven, Conn.,
a corporation of Maryland

Application July 27, 1949, Serial No. 107,049

20 Claims. (Cl. 246—251)

1

This invention relates to electric circuit controllers operable when attached to a toy railroad track by the weight of a passing toy train.

One object of the invention is to provide a circuit controller for this purpose in the form of a simple compact unit of thin proportion whose entire structure may be borne by and beneath a flexible span of toy track rails between the usual cross ties or sleepers that serve to hold the rails in elevated relation to the underlying support surface or "road" bed.

Another object is to provide releasable fastening means to attach and detach a unit of this kind readily at any desired location along the course of a conventional toy track for making its location variable therealong at will.

Another object is to provide a circuit controller borne by a toy track and whose relatively movable circuit controlling contacts are all carried by a common rigid switch base so that they may all be raised and lowered in unison with such base in the upward and downward flexing of a resilient span of track caused by the weight of a passing toy train.

Another object is to construct the unitary switch base preferably as a single body of insulative material thereby to do away with extra insulators for spacing its electrically alive parts from each other or from the conductive rails of the track.

A further object is to enable the circuit controlling contacts to be located between, instead of laterally aside from, the rails of the track.

Another object is to make possible minute and finely controlled manually adjustable variations of resilient resistance to the separation of one circuit controlling contact from another circuit controlling contact and to the approach of one circuit controlling contact toward another circuit controlling contact.

Still another object is to enable all binding posts for the connection of electric wires to the controller to be carried in fixed relation to one another on the common rigid structure of the switch base.

The foregoing and other objectives of the improvements will appear in greater detail in the following description of a preferred embodiment of the invention such description having reference to the appended drawings, wherein:

Fig. 1 is a perspective view drawn on larger than full scale showing a circuit controller embodying the present improvements attached in place beneath two toy track rails of which only fragments are shown.

Fig. 2 is a plan view in preferred actual size showing the complete controller unit of Fig. 1.

Fig. 3 is a bottom plan view of the same unit showing an extended length of the track rails held separated by one of the sleepers.

2

Fig. 4 drawn on an enlarged scale is a side elevation of toy track rails broken away to indicate contraction of their length supported by sleepers and carrying the improved circuit controller shown in section on the plane 4—4 in Fig. 2, looking in the direction of the arrows, the position of parts being as when the track is not loaded by weight of a passing train.

Fig. 5 is a side elevation of the structure in Fig. 4 showing the positions assumed by the parts when the track rails are temporarily flexed downward by the weight of toy rolling stock.

Fig. 6 is a view taken in section on the plane 6—6 in Fig. 2 looking in the direction of the arrows and is drawn on the same enlarged scale as Figs. 4 and 5.

Fig. 7 is an enlarged perspective view of parts of the assembled structure shown in Fig. 1 with the tension adjusting nut broken away to expose its point of pressure exerting engagement.

In the drawings a section of the length of a conventional toy railroad track is shown consisting of slightly flexible resilient parallel traction rails 12 and 13 supported at a fixed gauge of lateral separation in a conventional manner on sleepers or crossties 14 which are spaced sufficiently apart along the rails to permit both track rails to flex somewhat downward between the sleepers as indicated in Fig. 5. This occurs when the rails in unison receive the weight of rolling stock wheels 15 as the latter ride over or come to rest at the location of the improved circuit controller.

The controller unit may have the following preferred construction. The switch base 18 is preferably an integral relatively rigid slab-like body of molded plastic or other insulative material shaped to provide a central depending boss 19 containing a vertical bore at 20 and a counterbore 21 at its top. This boss and bore afford guide bearing for an actuator 22 which is freely slidable up and down therein, herein chosen as illustrative of any equivalent actuating medium so termed in the claims of this application. Within the broader aspects of the invention actuator 22 may have sundry shapes and dispositions relative to switch base 18 other than that herein shown. Actuator 22 is in the nature of a plunger whose head 23 occupies the counterbore 21 and whose bottom end has riveted or otherwise fixed thereto a landing foot here shown as a thin broad horizontal disc 24.

Somewhat above the top surface of switch base 18 and maintained in proper alignment by a recessed seat 26 there is secured to such base by rivet 27 not only the anchored end of an electrically conductive spring leaf circuit controlling contact member 28 which extends diametrically across counterbore 21 and overhangs head 23 of plunger 22 but also the anchored end of a super-

imposed more flexible and resiliently weaker leaf spring 25 most of whose length lies in somewhat vertically separated relation to contact member 28. Leaf spring 25 may be only about half the thickness of contact member 28 and its dipped formation 38 bears downward against member 28 for imparting variable auxiliary tension thereto only at a single location in the latter's length. Member 28 carries and presents both upwardly and downwardly at its free end contact point or points 29. This contact point is normally positioned as in Fig. 4 where it is shown to engage a stationary circuit terminal stud or cooperative contact member 30 fixed on the base 18. In Fig. 5 contact 29 is shown differently positioned to engage a higher circuit terminal 31 which also is secured to base 18 on the recessed aligning seat 33 by rivet 32. The natural combined tendency of the self contained resilience in member 28 and the self contained auxiliary resilience in leaf spring 25 acts to maintain contacts 29 and 30 normally in mutual engagement. The rigidity of switch base 18 is relative in comparison with the flexibility of spring leaf 28 and has that meaning where used in the claims hereof.

Leaf spring 25 is tensioned to adjustable degrees, and its resistance to flexing is thereby altered, by means of a super-imposed pressor nut 34 having threaded engagement with a screw stud 35 which is fixedly embedded in switch base 18. Nut 34 can conveniently be reached and turned by the operator's fingers applied to its scalloped head or handle knob 36. The threaded length of stud 35 projects upward through free clearance apertures 37 in contact member 28 and 48 in leaf spring 25. Preferably nut 34 does not bear directly on the broadside surface of leaf spring 25 but instead bears on an upwardly embossed spot 39 thereon.

By means of bus bars 40, 41 and 42 on the bottom face of switch base 18 the flexible spring leaf contact member 28 and the stationary circuit terminals 30 and 31 are electrically connected respectively to binding posts 43, 44 and 45, to which posts lead wires such as 46 and 47 are attachable. This enables the make-and-break contact mechanism of the unit to be located between the track rails while its binding posts are displaced to a trackside location.

Switch base 18 is upwardly tongued at 49 to provide a horizontal groove 50 in which a bottom or foot flange 17 of rail 12 may be lodged removably as best shown in Fig. 6. A bottom or foot flange 17 of the other rail 13 is correspondingly lodged beneath a fastening cam 51 that is pivotally anchored by stud 52 to the switch base. The rail holding surfaces 53 and 53' of cam 51 are cam shaped so as to press wedgingly against the base flange and web of track rail 13 when the cam is swung clockwise in Figs. 1 and 2. Because the crossties or sleepers 14 maintain the track rails spaced apart against lateral pressure of cam surface 53' toward the left, such pressure forces the flange of rail 12 edgewise against the bevelled surface 54 of base lug 49 and at the same time cam surface 53 wedges down against the bottom flange of rail 13, thus holding the switch base 18 upward firmly against the bottom flanges of both rails. This quick means of attachment and detachment holds the switch base removably in fixed relation to the rails at any chosen location in the course of the track.

The train operated action of the circuit controller is best apparent from Figs. 4 and 5. In the former figure the plunger foot 24 may or need

not rest lightly on the bed surface 16 which may comprise the top of a table, a floor carpet, or what not, representative of the "road bed" of a railroad. In Fig. 4 it is also apparent there is no tendency of the plunger head 23 to press upwardly on spring leaf 28. Hence contacts 29 and 30 remain normally in mutual engagement to complete a circuit from binding post 43 to binding post 44. When the wheels 15 of toy rolling stock (not shown) pass over the rails 12 and 13 directly above the switch base 18, the rails temporarily bow slightly downward between sleepers as indicated in Fig. 5 causing the switch base 18 as a whole to sink to a lowered position shown in Fig. 5.

In this action of the switch base the plunger foot 24 is blocked against downward movement because it rests on or encounters the bed surface 16. Hence the plunger head 23 cannot accompany downward movement of contact member 28 and the latter is forced to flex upward by the now immovable plunger head so that carried contact point 29 is forced to leave engagement with contact 30 and may be caused to move upward far enough to engage overlying stationary contact 31 instead. Thus circuit can be broken between binding posts 43 and 44 and circuit made between binding posts 43 and 45, as a mere result of the arrival of rolling stock wheels in the position shown in Fig. 5. In this action neither said wheels nor any part of a toy train need be brought into contact with any extraneous track or trackside object and the electric circuit governed by the improved controller does not pass through any wheel or other structure of the rolling stock.

When the circuit controller is installed as a unit at various chosen locations along a course of track, variation may be encountered in the degree of flexure of the tracks that will cause contacts 29, 30 to be opened. Also it may be desired to predetermine whether such deflection shall or shall not operate to close contacts 29, 31. The pressor nut 34 is used for this and other adjustive purposes and may first be retracted upward on the screw thread of stud 35 until it is free from engagement with leaf spring 25. After the switch base 18 has been securely anchored to the track rails in its chosen location by the fastening action of cam 51, nut 34 may be set down to such degree of pressure against spot 39 on leaf spring 25 that the resistance of the latter to forces tending to flex contact member 28 upwardly can be predetermined and this will predetermine what response member 28 will make to the downward thrust of the weight of the rolling stock on the track rails. Thus the circuit controlling response of the unit to a given track situation and to a given weight of rolling stock can be varied for different desired circuit controlling results.

The appended claims are directed to and intended to cover not only the particular embodiment of the invention illustrated and described herein but also all obvious or well-known variations of and equivalents for the shapes, sizes and relationship of parts coming within the broadest interpretation of the language used in the claims.

I claim:

1. In an electric circuit controller to be operated by the passing of toy train rolling stock over a toy railroad track of the type comprising resilient rails supported on and held separately by spaced sleepers adapted to rest on a bed surface toward which the rails deflect responsively to weight of said rolling stock, the combination of

a switch base adapted to be carried by said rails in elevated relation to said bed surface, relatively movable circuit controlling members on said switch base, and an actuating medium carried by said switch base in operative relation to at least one of said members and in movable relation to said base projecting from the latter in position to be blocked against movement by the bed surface when said base is lowered by downward deflection of said rails.

2. In an electric circuit controller to be operated by the passing of toy train rolling stock over a toy railroad track of the type comprising resilient rails supported on and held separated by spaced sleepers adapted to rest on a bed surface toward which the rails deflect responsively to weight of said rolling stock, the combination of, a switch base comprising an integral rigid body adapted to be carried by said rails in elevated relation to said bed surface, relatively movable circuit controlling members on said switch base, and an actuating medium carried by said switch base in operative relation to at least one of said members and in movable relation to said base projecting from the latter in position to be blocked against movement by the bed surface when said base is lowered by downward deflection of said rails.

3. In an electric circuit controller to be operated by the passing of toy train rolling stock over a toy railroad track of the type comprising resilient rails supported on and held separated by spaced sleepers adapted to rest on a bed surface toward which the rails deflect responsively to weight of said rolling stock, the combination of, a switch base comprising an integral rigid body of insulating material adapted to be carried by said rails in elevated relation to said bed surface, relatively movable circuit controlling members on said switch base, and an actuating medium carried by said switch base in operative relation to at least one of said members and in movable relation to said base projecting from the latter in position to be blocked against movement by the bed surface when said base is lowered by downward deflection of said rails.

4. In an electric circuit controller to be operated by the passing of toy train rolling stock over a toy railroad track of the type comprising resilient rails supported on and held separated by spaced sleepers adapted to rest on a bed surface toward which the rails deflect responsively to weight of said rolling stock, the combination of, a switch base adapted to be carried by said rails in elevated relation to said bed surface, relatively movable circuit controlling members on said switch base, and an actuating medium carried by said switch base in operative relation to at least one of said members and constrained to rectilinear sliding movement relative to said base projecting from the latter in position to be blocked against movement by the bed surface when said base is lowered by downward deflection of said rails.

5. In an electric circuit controller to be operated by the passing of toy train rolling stock over a toy railroad track of the type comprising resilient rails supported on and held separated by spaced sleepers adapted to rest on a bed surface toward which the rails deflect responsively to weight of said rolling stock, the combination of, a switch base adapted to be carried by said rails in elevated relation to said bed surface, relatively movable circuit controlling members on said switch base, and a plunger slid-

able vertically through the said switch base having a head end in operative relation to one of the said circuit controlling members and having a foot end positioned to be blocked by the said bed surface against downward movement when the said track rails deflect downward.

6. In an electric circuit controller to be operated by the passing of toy train rolling stock over a toy railroad track of the type comprising resilient rails supported on and held separated by spaced sleepers adapted to rest on a bed surface toward which the rails deflect responsively to weight of said rolling stock, the combination of, a switch base comprising an integral rigid body of insulating material adapted to be carried by said rails in elevated relation to said bed surface, relatively movable circuit controlling members on said switch base, and a plunger slideable vertically through the said switch base having a head end in operative relation to one of the said circuit controlling members and having a foot end positioned to be blocked by the said bed surface against downward movement when the said track rails deflect downward.

7. In an electric circuit controller to be operated by the passing of toy train rolling stock over a toy railroad track of the type comprising resilient rails supported on and held separated by spaced sleepers adapted to rest on a bed surface toward which the rails deflect responsively to weight of said rolling stock, the combination of, a switch base adapted to be carried by said rails in elevated relation to said bed surface, relatively movable circuit controlling members on said switch base carried thereabove between said track rails, and an actuating medium carried by said switch base in operative relation to at least one of said members and in movable relation to said base projecting from the latter in position to be blocked against movement by the bed surface when said base is lowered by downward deflection of said rails.

8. In an electric circuit controller to be operated by the passing of toy train rolling stock over a toy railroad track of the type comprising resilient rails supported on and held separated by spaced sleepers adapted to rest on a bed surface toward which the rails deflect responsively to weight of said rolling stock, the combination of, a switch base comprising an integral rigid body of insulating material adapted to be carried by said rails in elevated relation to said bed surface, relatively movable circuit controlling members on said switch base carried thereabove between said track rails, and an actuating medium carried by said switch base in operative relation to at least one of said members and in movable relation to said base projecting from the latter in position to be blocked against movement by the bed surface when said base is lowered by downward deflection of said rails.

9. In an electric circuit controller to be operated by the passing of toy train rolling stock over a toy railroad track of the type comprising resilient rails supported on and held separated by spaced sleepers adapted to rest on a bed surface toward which the rails deflect responsively to weight of said rolling stock, the combination of, a switch base adapted to be carried by said rails in elevated relation to said bed surface, relatively movable circuit controlling members on said switch base carried thereabove between said track rails, and a plunger slideable vertically through the said switch base having a head end in operative relation to one of the said circuit

controlling members and having a foot end positioned to be blocked by the said bed surface against downward movement when the said track rails deflect downward.

10. In an electric circuit controller to be operated by the passing of toy train rolling stock over a toy railroad track of the type comprising resilient rails supported on and held separated by spaced sleepers adapted to rest on a bed surface toward which the rails deflect responsively to weight of said rolling stock, the combination of, a switch base adapted to be carried by said rails in elevated relation to said bed surface, relatively movable circuit controlling members on said switch base including an elongated electrically conductive spring leaf carried on the top thereof, an actuating medium carried by said switch base including a plunger slidably vertically through the latter having a head end overhung by said spring leaf in a manner to operatively engage the same, and having a foot end projecting from said base in position to be blocked by said bed surface against downward movement when said base is lowered by downward deflection of said rails.

11. In an electric circuit controller to be operated by the passing of toy train rolling stock over a toy railroad track of the type comprising resilient rails supported on and held separated by spaced sleepers adapted to rest on a bed surface toward which the rails deflect responsively to weight of said rolling stock, the combination of, a switch base adapted to be carried by said rails in elevated relation to said bed surface, relatively movable circuit controlling members on said switch base including an elongated electrically conductive spring leaf carried on the top thereof, an actuating medium carried by said switch base including a plunger slidably vertically through the latter having a head end overhung by said spring leaf in a manner to operatively engage the same, and having a foot end projecting from said base in position to be blocked by said bed surface against downward movement when said base is lowered by downward deflection of said rails, together with a device for tensioning said spring leaf including an adjustable resilient pressor element bearing against said spring leaf in a broadside direction.

12. In an electric circuit controller to be operated by the passing of toy train rolling stock over a toy railroad track of the type comprising resilient rails supported on and held separated by spaced sleepers adapted to rest on a bed surface toward which the rails deflect responsively to weight of said rolling stock, the combination of, a switch base adapted to be carried by said rails in elevated relation to said bed surface, relatively movable circuit controlling members on said switch base including an elongated electrically conductive spring leaf carried on the top thereof, an actuating medium carried by said switch base including a plunger slidably vertically through the latter having a head end overhung by said spring leaf in a manner to operatively engage the same, and having a foot end projecting from said base in position to be blocked by said bed surface against downward movement when said base is lowered by downward deflection of said rails, together with a device for tensioning said spring leaf including an adjustable resilient pressor element bearing against said spring leaf in a broadside direction, and a screw threaded member cooperative with

said resilient pressor element in a manner to flex the same.

13. In an electric circuit controller to be operated by the passing of toy train rolling stock over a toy railroad track of the type comprising resilient rails supported on and held separated by spaced sleepers adapted to rest on a bed surface toward which the rails deflect responsively to weight of said rolling stock, the combination of, a switch base adapted to be carried by said rails in elevated relation to said bed surface, relatively movable circuit controlling members on said switch base including an elongated electrically conductive spring leaf carried on the top thereof, an actuating medium carried by said switch base including a plunger slidably vertically through the latter having a head end overhung by said spring leaf in a manner to operatively engage the same, and having a foot end projecting from said base in position to be blocked by said bed surface against downward movement when said base is lowered by downward deflection of said rails, together with a device for tensioning said spring leaf including an adjustable resilient pressor element comprising a leaf spring substantially thinner than said spring leaf and bearing thereagainst at a single location in the flexible length of said spring leaf.

14. In an electric circuit controller to be operated by the passing of toy train rolling stock over a toy railroad track of the type comprising resilient rails supported on and held separated by spaced sleepers adapted to rest on a bed surface toward which the rails deflect responsively to weight of said rolling stock, the combination of, a switch base adapted to be carried by said rails in elevated relation to said bed surface, relatively movable circuit controlling members on said switch base including an elongated electrically conductive spring leaf carried on the top thereof, an actuating medium carried by said switch base including a plunger slidably vertically through the latter having a head end overhung by said spring leaf in a manner to operatively engage the same, and having a foot end projecting from said base in position to be blocked by said bed surface against downward movement when said base is lowered by downward deflection of said rails, together with a device for tensioning said spring leaf including an adjustable resilient pressor element comprising a leaf spring substantially thinner than said spring leaf and bearing thereagainst at a single location in the flexible length of said spring leaf, said tensioning device also including a screw threaded member cooperative with said leaf spring in a manner to flex the same.

15. In an electric circuit controller to be operated by the passing of toy train rolling stock over a toy railroad track of the type comprising resilient rails supported on and held separated by spaced sleepers adapted to rest on a bed surface toward which the rails deflect responsively to weight of said rolling stock, the combination of, a switch base adapted to be carried by said rails in elevated relation to said bed surface, relatively movable circuit controlling members on said switch base carried thereabove between said track rails, and an actuating medium carried by said switch base in operative relation to at least one of said members and in movable relation to said base projecting from the latter in position to be blocked against movement by the bed surface when said base is lowered by downward deflection of said rails, together with binding posts carried

by said switch base in a location aside from the said track, and bus bars mounted on the bottom of said switch base extending crosswise one of the said rails from the said circuit controlling contacts to said binding posts respectively.

16. In an electric circuit controller to be operated by the passing of toy train rolling stock over a toy railroad track of the type comprising resilient rails supported on and held separated by spaced sleepers adapted to rest on a bed surface toward which the rails deflect responsively to weight of said rolling stock, the combination with said rails and sleepers of, a switch base adapted to be carried by said rails in elevated relation to said bed surface, relatively movable circuit controlling members on said switch base, and an actuating medium carried by said switch base in operative relation to at least one of said members and in movable relation to said base projecting from the latter in position to be blocked against movement by the bed surface when said base is lowered by downward deflection of said rails, said sleepers being spaced sufficiently far apart along said rails to enable the latter to deflect temporarily downward and carry said switch base therewith into closer proximity to said bed surface responsively to the weight of toy rolling stock borne by said rails between said sleepers.

17. In an electric circuit controller to be operated by the passing of toy train rolling stock over a toy railroad track of the type comprising resilient rails supported on and held separated by spaced sleepers adapted to rest on a bed surface toward which the rails deflect responsively to weight of said rolling stock, the combination with bottom laterally projecting foot flanges of said rails of, a switch base adapted to be carried by said rails in elevated relation to said bed surface, a rigid anchorage tongue on said switch base in raised relation to the top surface thereof retainingly overhanging the foot flange of one of said rails, clamping means operative to hold the last said foot flange under said anchorage tongue, relatively movable circuit controlling members on said switch base, and an actuating medium carried by said switch base in operative relation to at least one of said members and in movable relation to said base projecting from the latter in position to be blocked against movement by the bed surface when said base is lowered by downward deflection of said rails.

18. In an electric circuit controller to be operated by the passing of toy train rolling stock over a toy railroad track of the type comprising resilient rails supported on and held separated by spaced sleepers adapted to rest on a bed surface toward which the rails deflect responsively to weight of said rolling stock, the combination with bottom laterally projecting foot flanges of said rails of, a switch base adapted to be carried by said rails in elevated relation to said bed surface, a rigid anchorage tongue on said switch base having an oblique wedging surface rising fixedly from the top surface of said switch base and overhanging the foot flange of one of said rails, a wedging device carried movably by said switch base in position to engage the track in a manner to thrust the last said rail flange laterally against said oblique camming surface of said anchorage tongue, relatively movable circuit controlling members on said switch base, and an actuating medium carried by said switch base in operative

relation to at least one of said members and in movable relation to said base projecting from the latter in position to be blocked against movement by the bed surface when said base is lowered by downward deflection of said rails.

19. In an electric circuit controller to be operated by the passing of toy train rolling stock over a toy railroad track of the type comprising resilient rails supported on and held separated by spaced sleepers adapted to rest on a bed surface toward which the rails deflect responsively to weight of said rolling stock, the combination with upright webs and bottom laterally projecting foot flanges of said rails of, a switch base adapted to be carried by said rails in elevated relation to said bed surface, a rigid anchorage tongue on said switch base in fixed raised relation to the top surface thereof retainingly overhanging the foot flange of a first one of said track rails, a rotary cam having plural camming surfaces eccentrically pivoted on and above the top surface of said switch base in position to overlie the foot flange of a second one of said track rails, one of said camming surfaces being disposed to thrust laterally against the upright web of said second one of said rails in a direction to maintain said flange of said first one of said rails under said tongue and the other of said camming surfaces being disposed to overlie and thrust downward on said foot flange of said second one of said rails, relatively movable circuit controlling members on said switch base, and an actuating medium carried by said switch base in operative relation to at least one of said members and in movable relation to said base projecting from the latter in position to be blocked against movement by the bed surface when said base is lowered by downward deflection of said rails.

20. In an electric circuit controller to be operated by the passing of toy train rolling stock over a toy railroad track of the type comprising resilient rails supported on and held separated by spaced sleepers adapted to rest on a bed surface toward which the rails deflect responsively to weight of said rolling stock, the combination with upright webs and bottom laterally projecting foot flanges of said rails of, a switch base adapted to be carried by said rails in elevated relation to said bed surface, a rigid anchorage tongue on the said switch base having an oblique wedging surface rising from the top surface of said switch base and overhanging the foot flange of one of said rails, and a rotary cam eccentrically pivoted on and above the top surface of said switch base in position to overhang the foot flange of another of said rails and thrust laterally against the upright web of one of the last said rails in a direction to force said rail flange against said oblique wedging surface of said tongue thereby to draw and maintain said switch base firmly against the bottom of the foot flange of the first said rail, relatively movable circuit controlling members on said switch base, and an actuating medium carried by said switch base in operative relation to at least one of said members and in movable relation to said base projecting from the latter in position to be blocked against movement by the bed surface when said base is lowered by downward deflection of said rails.
